ADJUSTABLE CHAIR

Filed June 19, 1929

Inventor

Earl Cross,

By J. Howard Flint.

Attorney

UNITED STATES PATENT OFFICE

EARL CROSS, OF RENO, NEVADA

ADJUSTABLE CHAIR

Application filed June 19, 1929. Serial No. 372,118.

This invention pertains to an article of manufacture and to certain component parts thereof, particularly as embodied in a chair or seat suitable to be attached to various supporting structures. More particularly it is exemplified in an adjustable chair adapted to be attached to a variety of other seats. In certain forms the chair is reducible, by folding, to relatively small dimensions. Also in the same or other forms it is convertible into a swing seat, or adaptable to different types of attachment to a supporting structure.

A salient object of the invention is to provide such an attachable chair as may be sustained by the seat of larger chairs without imposing any considerable strain on the back of the larger chair. Another object is to support an attached chair without regard to the height or width or configuration of the back of the larger chair. Yet another object is to obtain vertical adjustments of the supported seat without changes of the supports of the chair as a whole. Another object is to provide a supporting member for the seat proper that will be the means of adjusting the seat vertically and will also serve as a pivoting member by which the seat may be adjusted angularly or be rotated to a folded position. Another object is to provide an adjustable, folding seat that is susceptible of large scale production as a result of the simplification herein presented and of the introduction of novel features of co-operation in the assembled structure. Other objects and advantages will appear with an understanding of the invention as set forth in the accompanying illustrative embodiments and drawings and as particularly pointed out in the appended claims.

In order to illustrate this invention fully so that others may understand its practices, certain embodiments are described which constitute present preferred forms of various features of the invention. Such illustrations are not intended to be restrictive however. Reference may be had to the accompanying diagrammatic drawings forming part of this specification, in which:

Fig. 1 is a vertical section of the auxiliary chair proper with a side view of a supporting

chair having one back member broken away.

Fig. 2 is a front elevation of the auxiliary chair supported by a larger chair.

Fig. 3 is a plan view of the chair with a supporting structure and a portion of the securing means in section. 55

Fig. 4 is a detail in side view of the securing means, and of the fastening for a side arm.

Fig. 5 is a detail in section of the top of the chair back with means adaptable to different types of devices for suspending the chair. 60

Fig. 6 is one form of supporting hook.

By reference to Fig. 1 it is apparent that this auxiliary chair comprises a generally 65

vertically disposed back member 11. The lower part of this member is recessed for a portion of its length, and over this recess is secured a plate slotted at 12 and notched with a desirable number of notches 13. It will be

understood that the invention is not restricted as to the number or shape of the back member, though two such are shown and as shown are positioned at the two rear corners of the chair. 70

Neither is the invention restricted to the type of slotted and notched portion, for it is apparent that it may be some integral portion of the rear member, or that other pivot adjustment may be provided. In the preferred embodiment shown there is however sufficient 75

space for movement in the slot 12 of the shank of the head 15 of a pivoted arm 14. The rear of this arm 14 preferably slides in the recessed portion of the back. This arm, or arms, 14

preferably is curved downwardly from the rear and then normally extended horizontally as shown in Fig. 1. It thus supports side pieces 16, upon which rests the seat 17. By 80

engagement of the projection of the head 15 in one notch or another the seat is adjusted vertically; while by rotation of the arm the seat is folded to the back or unfolded without disturbing its vertical adjustment. With the 85

back members 11 forming legs for the chair it is apparent that the weight of an occupant is supported primarily by these legs. Also it is apparent that vertical adjustment of the 90

seat is relative to the seat 18 of a supporting chair upon which the auxiliary chair ordinarily will bear. To supply a stop to the 95

tendency of the arm 14 to rotate downwardly, preferably the side member 16 to which 14 is secured abuts at the rear as shown against the back 11 when the arm 14 is horizontal. Other types of stop however may be contemplated within the broader scope of this invention.

The upper portion of the back members 11 carries a side retaining arm 19, and this preferably is readily adjustable to grip the back of the supporting chair 20. In the illustrative embodiment, each of the two arms 19 shown comprises a straight portion and a curved portion, the latter normally being adjustable to bear forward against the back of the supporting chair in response to the tendency to forward tilting of the auxiliary chair. Preferably this straight portion of arm 19 extends through a coil spring 21, which spring is retained on the arm 19 by an enlargement at the end thereof. As shown in Fig. 3, the outer end of the spring engages a plate 22 on the outer side of the member 11 of the auxiliary chair so that while the arms 19 may be pulled out for engaging the support 20, on being released they simply will be retracted to resting position. As is shown, two arms 19 and their springs 21 are enclosed in a tubular element 23 between the corner members 11.

In order to assure a minimum of undesirable slipping of the arms 19, and to assist them to be adjusted to different forms of supporting structure, a locking structure is provided for them. In Fig. 4 this is shown as a cam arm 24 on the side member 11, rotatable to wedge the arm 19 against turning.

As it may be desired to eliminate noise or to avoid marring other furniture, there are provided appropriate cushion members 24', such as rubber pads on the bottoms of the legs 11; also rubber tubing over the curved portion of the side arms 19.

From the description thus far given it will become apparent that this auxiliary chair is not limited to being attached to one larger chair, but that a particularly useful application will be in sustaining it between two other chairs. For example, parents occupying two larger chairs may seat a child between them, resting the supporting members 11 of the child's chair upon each of the larger chairs and engaging the sustaining side arm 19 behind the backs of the two larger chairs. The structure of the supporting chair thus is of minimal importance. For example, light chairs with curved backs are just as effective supports as heavy straight backed ones.

In order to adapt this auxiliary chair further to accommodate young children, sides may be provided having certain features that make for safety as well as for compactness. By reference to Figs. 1 and 2 it is seen that these sides comprise a base member 25, secured by inner hinges to the seat 17. From Fig. 3 it is clear that the back of a top rail,

sustained by the base member upon vertical elements 26, extends beyond the inner edge of leg 11 so that its outward swing is limited thereby. Thus a substantial stop is provided for inadvertent opening of the folding sides beyond their vertical position. In order however that these sides may reach a vertical position their rear outer corners are recessed to clear the members 11, as is shown in Fig. 3. And in order that inward swinging of the sides may be under simple, positive control they preferably are provided with suitable catches to engage legs 11. In the form shown in Figs. 3 and 4, these simply are slide bolts 28 projecting along the outer sides of members 11 when the arms 27 are raised to the vertical. In Fig. 2, the folded position of the sides upon the seat is shown in dotted lines. It is evident the position of these arms between the bracket 14 and the rear leg 11 controls the upward rotation of the bracket 14 for disengagement from any notch 13.

A tray 29 is provided, so arranged as to prevent undesirable folding of the arms when the bolts 28 are retracted. The edges of the tray are tongued, and the side rail 27 is provided with grooves to receive the tray in sliding engagement from the front. The front ends of rail 27 are provided with deformed or eccentric buttons 30, which may be turned to retain the tray in its inserted position. In Fig. 2 one such button, with thumb grips, is shown in position to permit the withdrawal of the tray and the other button turned to closed position.

Further with reference to the tray, the chair is provided with a storage space made possible by flanging the horizontal arm 14 inwardly and mounting it in spaced relation to the seat 17. Thus there are supports for the tray between the elements 16 to secure it in any position of the seat. Suitable buttons to retain the tray may also be provided here if desired.

In order to sustain the chair from other types of support, the tops of the vertical members 11 may be fashioned to receive hook elements. In one form, as shown in Figs. 1 and 5, a metal plate 30 is secured to the top by portions extending downwardly and engaging the top by rivets or the like. The plate is drilled, preferably in its front half, and suitably threaded to receive eye bolt 31, and bushing 32. With this type of fastening the chair may be suspended by ropes from bolts 31 and from similar bolts 33 at the bottom to form a swing, for example. By removing bolts 31 and substituting a longer hook member 34, of the type shown in Fig. 6, the chair may be suspended from other supporting elements, for example from the back of an auto seat. Where this longer hook is employed the vertical members preferably will be bored to receive the end of the hook 34 for a suitable distance below the

plate. It is evident that in certain cases the bushing 32 may be dispensed with and members 31 or 34 of suitable diameter be secured directly to the top.

5 In operation the chair is readily adjusted to accommodate a person of given height, say a baby of less than a year. The seat 17 is raised to its highest position by engaging the head 15 of supporting arm 14 in the highest notch 13. As long as this elevation is suitable, it is retained; but during that time the chair may be folded and carried about or unfolded as desired. When an older child is to be accommodated, the seat is lowered by sliding the head 15 down the slot 12 to a lower notch. At this elevation, as at others, the head 15 acts as a pivot for folding the seat or for sustaining the occupant. With a child of yet greater height the seat is lowered further to the proper notch. Thus the one chair will accommodate a child from the time it is first able to sit up until it is of such age that its height permits it to use an ordinary chair advantageously.

25 The chair having been adjusted by elevating the seat as desired, the seat may be folded by releasing the thumb bolts 28 of the side rail 27 and, with tray 29 slid beneath the seat, turning the sides in upon the seat, then folding this assemblage to the back about the pivot 15. If desired the chair may be left in that position, in engagement by the side hooks 19 with a supporting chair, and yet leaving space for an adult in the larger chair. Or 35 it may be removed entirely from the larger chair, before or after folding.

From folded position the chair may be set up quickly by turning down the seat, raising the side arms and locking them simply by pushing the bolts 28 backwards. The engaging arms 19 as quickly may be sprung out and locked behind the sides of their support, such as the sides of a chair, or of two chairs where the auxiliary chair is placed between two chairs.

This description of the best practice and construction now known under this invention is presented in accordance with the patent statutes. However, in referring to these 50 illustrative embodiments of this invention, restrictions have not been implied thereby. One particular structure was made of wood with an angle iron support and restricted to a weight of about five pounds. However 55 wood need not necessarily be used, as it will be within ordinary skill in the art to construct this chair of suitable metal parts. Also various features may be omitted or modified without altering the scope of this invention.

60 It is intended to claim broadly such features of this invention as the prior art permits. Accordingly,

What is claimed is:

1. A portable folding chair adapted for 65 principal support at the rear thereof, com-

prising a rear leg containing a vertical series of open notches, a seat-supporting bracket adjustably mounted on the leg forwardly thereof by a pivotal, cantilever support comprising a lug extending laterally from the bracket to engage any selected notch and a projection extending laterally from the bracket to bear against the chair leg, and means controlling adjustment of the seat along the series of notches, comprising a 70 rigid arm foldably mounted above the bracket for bearing in raised position against the leg and bracket to prevent swinging the bracket upwardly and in folded position affording space for the bracket to be rotated 75 upwardly for disengagement from a notch.

2. A portable folding chair adapted for principal support at the rear thereof, comprising a rear leg containing a vertical series of open notches, a seat-supporting bracket 80 adjustably mounted on the leg forwardly thereof by a pivotal, cantilever support comprising a lug extending laterally from the bracket to engage any selected notch and a projection extending laterally from the bracket to bear against the chair leg, means controlling adjustment of the seat along the 85 series of notches, comprising a rigid arm foldably mounted above the bracket for bearing in raised position against the leg and bracket to prevent swinging the bracket upwardly and in folded position affording space for the bracket to be rotated 90 upwardly for disengagement from a notch, and a pair of retaining arms retractably mounted from the rear leg in opposed relation to each other across the rear of the chair, each arm terminating outwardly in an enlarged hook for 95 external engagement to prevent the chair from tilting, and a spring engaging the inner portion of each arm and mounted for drawing the hook toward the leg.
